W. T. PYLE.

STEP LADDER.

APPLICATION FILED JAN. 23, 1915.

1,191,922.

Patented July 18, 1916.

UNITED STATES PATENT OFFICE.

WILLIAM T. PYLE, OF PEKIN, ILLINOIS, ASSIGNOR TO SAFETY FOLDING LADDER COMPANY, OF PEKIN, ILLINOIS, A CORPORATION OF ILLINOIS.

STEP-LADDER.

1,191,922.

Specification of Letters Patent. Patented July 18, 1916.

Application filed January 23, 1915. Serial No. 3,994.

To all whom it may concern:

Be it known that I, WILLIAM T. PYLE, citizen of the United States, residing at Pekin, in the county of Tazewell and State 5 of Illinois, have invented certain new and useful Improvements in Step-Ladders; and I do hereby declare that the following is a full, clear, and exact description of the invention, which will enable others skilled in 10 the art to which it appertains to make and use the same.

This invention relates to improvements in step ladders. It pertains more particularly to a ladder in which safety is one of 15 the essentials.

One of the objects is to improve upon the folding construction of ladder illustrated in my Letters Patent issued Nov. 2, 1915, No. 1,158,716, by substituting a wide step for 20 the narrow substantially square form of step or rung of said application so as to give the user a wide rest for the foot without the necessity of holding or grasping a support for maintaining equilibrium on the 25 ladder.

Another object is to so construct the ladder that it will be perfectly rigid in use, the steps thereof being so formed that they will not interfere with the free operation of the 30 ladder nor the easy collapse of the same.

Another object is the provision in a step ladder of means whereby the distance between its rear supporting prop legs may be adjusted so as to give more or less spread 35 or in order to provide a wider base and a more perfect support on uneven surfaces. While the provision of adjustable rear or prop legs for a step ladder of the type herein to be described is not new, the particular 40 structure I employ herein is novel and exceedingly simple as will appear herein.

In addition to the objects the invention relates to certain details of construction in a step ladder that are new and novel.

45 Other objects and advantages will appear from the following specification aided by the accompanying drawing, in which,

Figure 1 shows the complete ladder in perspective; Fig. 2 is a side elevation of the

upper portion of the same; Fig. 3 is a front 50 elevation of a portion of the ladder illustrating the manner of its folding; Fig. 4 is a horizontal section of the front supporting legs showing the peculiar construction of one of the steps; and, Fig. 5 is a front elevation of the ladder showing the lateral spreading of the rear supporting legs and means for holding them in any desired adjustment.

A A represent two pairs of parallel members, each pair constituting a side rail of the step section of the ladder, the members of each pair being spaced at the bottom by means of spacing blocks B, for example, the spaces being substantially equal to the 65 greatest width of the steps to be employed. The steps are indicated at C and constitute the spacing members above the blocks for the pairs of members A throughout their upper portions and are secured in place at 70 their ends between the two pairs of members by bolts D which extend through them and the members at right angles to the length of the latter as clearly illustrated in Fig. 2. The bolts form the pivots for the several 75 steps and the structure thus created can be collapsed by moving the pairs of members A longitudinally in opposite directions and toward each other as indicated by the broken lines in Fig. 3.

It has been found in practice, that when the ladder is collapsed the steps, if of the same width throughout, will bind at their edges between the pairs of the members A by frictionally engaging the inner surfaces 85 thereof. It has also been found that the preferred way of preventing this binding is to remove a portion of the material from each edge of the step as indicated at C', particularly in Fig. 4, so that the only parts 90 of the steps that have a width equal to the distance between the members are their ends where they lie between said members. By this means the ladder may be easily folded and unfolded without the edges binding inside of the members A which would result more especially in damp weather when the materials, usually wood, naturally swell.

E E represent the rear supporting or prop legs of the ladder, each having secured to it at its upper end a hinge F, one portion G of which receives the upper bolt D, Fig. 2, 5 which constitutes a pivot about which the hinge and the leg may swing laterally.

The purpose of providing for this pivotal swinging motion is that it is often desired to spread the legs of the ladder in order to 10 provide a larger supporting base by increasing the area lying inside the several legs to provide a better support especially on uneven ground. The broken lines in Fig. 5 indicate several of the adjustments that 15 may be made.

H H represent two rods preferably of metal whose upper ends, for example, are pivoted to the prop legs E, their lower ends being each provided with a notch J extending 20 at right angles to its length.

K represents a series of pins or studs on each prop leg E with any one of which the rods H are adapted to engage by means of their said notches. In the continuous lines 25 in Fig. 5 it is observed that the rods engage the middle pins or studs, while in the outermost dotted lines the rods engage the uppermost pins or studs. Again, the innermost broken lines indicate an inner position of the 30 prop legs in which they may lie substantially parallel to the side rails made up of the members A. In this position the rods H engage the lowermost studs. By this or any other equivalent means, the prop legs E may 35 be positioned any distance apart to provide as wide a support as desired, it being understood that the customary jointed tie 40 braces L attached to the members A and rear prop will have sufficient spring or sufficient looseness to permit any desired spread of the said legs.

When the rods H are in engagement with the studs K, and the ladder is set up as 45 shown in Fig. 1 it is perfectly rigid and although the several legs may rest on very uneven ground, the racking motion provided by the pivotal relation of the steps will permit all four legs to be forced firmly upon the ground surface by the weight of the person. In order that this may readily result 50 the rods H, which are flexible, will spring or bow outward as the weight is imposed upon the steps, the prop legs E being caused to move slightly in a longitudinal direction 55 relatively to one another due to such uneven surface.

An advantage in providing the lateral adjustment of the legs E, also, is that while a wide spread for uneven surfaces can be made 60 the legs can be "narrowed in" even to the position where they will be parallel to the front members A as in Fig. 5, so that whenever the ladder is used in an aisle or passage the prop legs can be adjusted to the width

thereof which is an advantage that will be 65 appreciated.

In a folding ladder of this type where the front members must preferably be parallel in order to lie close together when folded it is an advantage to have a very wide and, in 70 fact, an unusually wide spread of the prop legs so that the center of gravity will be well inside the spread of the ladder.

As a provision against splitting of the upper ends of the prop legs E and the members A under strain imposed upon the upper bolt D, which is also the pivoting member of the hinge F as already described, I provide transverse bolts or rivets M shown clearly in Figs. 1 and 2. These bolts or rivets 75 prevent any tendency to splitting and provide an exceedingly strong structure in a ladder which is rendered practically indestructible even with the hardest usage or when left exposed to the elements. 80

The manner of pivoting the hinge F for the prop legs E by employing one of the pivot bolts D for the steps provides an exceedingly simple construction. First, the single bolt D passes through the hinge, both the 90 members A, and the step, making but one part to answer the two purposes besides forming a strong connection for the prop legs with no looseness such as would cause the structure to be "rickety" and unstable. 95 Again, the ladder is rendered more sturdy by this form of connection than though the hinge were attached to one of the members A which would flex more or less under the weight of the person using it. 100

The manner of adjusting the prop legs laterally on the bolts D and securing them in the position desired by means of the rods H is novel, the movement thereof relatively 105 in a longitudinal direction being permitted by the flexibility of the said rods H.

Narrowing the steps C between the members A so as to avoid friction between these parts is important. The least swelling of the wood caused by dampness renders a ladder of this type exceedingly difficult to set up for use after having been collapsed especially by women who are not strong, this arrangement being new and novel. 110

The steps fit snugly between the members A and have a bearing thereon the full width of the latter so that the structure is a perfectly rigid one when set up for use, the narrowed portion of the steps admitting of the free holding or collapsing. 115 120

Having thus described my invention, I claim:

In a step ladder, the combination of a pair of legs each consisting of a pair of spaced members, a series of steps pivoted at 125 their ends between said members, a bolt at each end of and constituting the pivots for one of the steps and extending through the

same and the said members, a prop leg for each of the first named legs, a hinge secured to each, the said bolt also extending through said hinge, the hinges and their prop legs adapted to swing laterally upon said bolts, and cross rods connected at opposite ends to opposite prop legs.

In testimony whereof I affix my signature, in presence of two witnesses.

WILLIAM T. PYLE.
